UNITED STATES PATENT OFFICE.

ORLAND D. ORVIS, OF NEW YORK, N. Y., ASSIGNOR TO ANNIE D. ORVIS, OF NEW YORK, N. Y.

SMOKE-CONSUMING FURNACE.

1,267,446.

Specification of Letters Patent.

Patented May 28, 1918.

Application filed October 23, 1916. Serial No. 127,115.

To all whom it may concern:

Be it known that I, ORLAND D. ORVIS, a citizen of the United States, residing at the city of New York, borough of Manhattan, county and State of New York, have invented a certain new and useful Smoke-Consuming Furnace, of which the following is a specification.

This invention pertains to furnaces for steam boilers, the essential feature of which consists of means for feeding steam and air into the products of combustion whereby the additional oxygen thus supplied commingles with the gaseous products and results in burning the carbon present in the smoke, thus securing an increased heating effect of the resulting gases which flow out of the stack or uptake in a thin substantially colorless vapor.

According to the present invention the flue rearwardly of the furnace chamber is divided by the presence of piers and arches erected upon the bridgewall and positioned below the boiler so as to produce a plurality of (two or more) of flues or throats through which the gaseous products of combustion are free to flow into the flue extending rearwardly beneath the boiler, whereby the escaping gases impinge the piers and arches as well as the bridgewall so as to become broken up in a measure and operate to heat up the material composing said piers and arches. Incased within the bridgewall, arches and piers so as to be protected thereby against the destructive effects of the heat and gases, are blast pipes which are arranged to substantially surround the individual flues or throats and are adapted to be supplied from a common feed pipe with steam and air.

A distinctive feature of the invention resides in the provision of blast outlets or nozzles so related to the flues or throats as to direct the steam and air in crossing paths with respect to the direction of flow of the gases through said flues or throats. Said blast outlets or nozzles are positioned to direct the steam and air through the top, bottom and opposite walls bounding the flues or throats, said blasts crossing or intersecting about in the middle of the flues or throats. Preferably, the vertical pipes embedded in the piers have the outlets or nozzles inclined to a central line drawn fore and aft through the throats or flues, and thus the

outlets or nozzles direct the blasts in inclined paths converging rearwardly with respect to the line of flow of the gases. The blasts from the nozzles thus intercept the outflowing gases in a manner to break up the currents and insure a thorough mixture of the steam and air with the gaseous products, thus supplying oxygen for burning the carbon in the smoke, and at the same time the steam and air thus blown into the escaping gases flow in the direction rearwardly from the furnace chamber, as a result of which the draft is increased to an appreciable extent.

The blast pipes are thoroughly incased within the brickwork in order to minimize the destructive effect of the heat and gases upon the metal pipes. The piers and arches can be readily erected upon the bridgewall and the blast pipes installed therein without resorting to skilled labor, thus enabling the smoke consumer to be applied economically to furnaces now in existence or to be built into new furnaces.

Other features and advantages of the invention will appear from the following description taken in connection with the drawings, wherein—

Figure 1 is a vertical longitudinal section through a furnace embodying the invention.

Fig. 2 is a vertical cross section on the line 2—2 of Fig. 1 looking in the direction of the arrow.

Fig. 3 is a horizontal section illustrating diagrammatically the inclined converging lines of flow of the steam and air from the nozzles in the piers.

Fig. 4 is a detail of one blast pipe showing a preferred form of the nozzle.

The grate 10 within the fire chamber 11 is forwardly of the bridgewall 12, and over the fire chamber and the bridgewall extends the boiler 13, all of which are or may be usual in the art. As shown, the bridge wall is provided on its upper surface with a curved breast 14.

The space or flue between the bridgewall and the boiler is divided by piers 15 and arches 16 into a series of flues or throats 17, whereby the gaseous products flowing over the bridgewall are in a measure divided or broken up by the piers and arches. Any desired number of piers 15 may be erected upon the bridgewall, but as shown in Fig. 2, I employ two piers positioned equi-distantly from each other, and each pier posi-

tioned for a like distance from the side wall of the fire chamber. The piers extend upwardly from the bridge wall and support the arches 16, from which arches rises the 5 usual wall 18 for the boiler 13, said piers and arches extending rearwardly along the bridgewall for a suitable distance, as shown in Fig. 1. It is apparent that the piers and arches are composed of firebrick or other 10 vitreous material suitable for the purpose, and, further, that piers and arches may be installed easily and quickly in existing furnaces or in new furnaces.

A blast pipe 20 extends horizontally 15 across the bridgewall and is embedded below the top surface thereof, said blast pipe being provided with a feed pipe 21 through which steam and air are blown by any suitable means. Rising from the blast pipe are 20 vertical pipes 22, 23, and connected to the upper ends of the vertical pipes is another horizontal pipe 24, the pipes 20, 22, 23 and 24 being preferably in the same vertical plane and all of said pipes being connected 25 by appropriate fittings, such as elbows and T-connections. The upper horizontal pipe 24 is incased within the masonry of the arches 16 and vertical wall 18, whereas the pipes 22 are installed within the side walls 30 of the furnace, and pipes 23 are incased within the masonry of piers 15, all as clearly shown in Fig. 2. The pipes 20, 22, 23 and 24, are arranged so as to extend substantially around the individual throats or flues 35 17, although said pipes are incased within the masonry of the furnace so as to be protected from the deteriorating influence of the heat by said masonry.

The lower pipe 20 is provided with a 40 series of upwardly facing outlets or nozzles 25; the upper pipe 24 is provided with another series of outlets or nozzles 26 which face downwardly, said nozzles 25, 26 of the lower pipe and the upper pipe respectively 45 being arranged obliquely to the line of flow of the gaseous products between the piers; the pipes 22 in the side walls are provided with horizontally positioned outlets 27 which face toward the side flues 17 and the 50 vertical pipes 23 are provided with outlets or nozzles 28, 29. In Fig. 4 of the drawings the blast outlet is shown in the form of a nozzle 30 attached to a T-coupling 31 forming a part of one of the blast pipes, said 55 nozzle having a curved mouth 32 which is formed with a slot 33 the direction of the slot in said nozzle being approximately parallel to the axis of the pipe to which the nozzle is attached. It is preferred to use a 60 nozzle of the form shown in Fig. 4, but it will be understood that I reserve the right to use any desired or appropriate nozzle. The outlets or nozzles from the blast pipes are positioned in suitable openings 34 provided in the masonry, as shown in Fig. 3.

The blast outlets or nozzles of the series of pipes are so positioned with respect to each flue or throat 17 that the inflowing air is directed across the throat or flue, the air flowing from said outlets or nozzles in 70 directions to intersect within the throat. The nozzles 28, 29 of pipes 23 are inclined to the direction of flow of the gaseous products through the flues or throats 17, and thus the air supplied by the nozzles 28, 29 75 converges rearwardly of the piers, the effect of which is to inject air into the gaseous products in the direction of their outflow from the grate chamber and to increase the draft through said grate chamber to a 80 material extent. Similarly, the nozzles in all the pipes should be positioned to direct the inflowing air in paths inclined to the line of flow of the gases, for the purposes stated.

When the furnace is in service the heat and gases flow from the chamber through the flues or throats 17 and thence over the bridgewall into the rear flue, the gases being in a measure broken up by contact with the piers and arches so that the piers, arches and bridgewall become heated by contact of the gases therewith. Air is blown by any suitable appliance into the pipe 20 and thence distributed through the pipes 22, 23, 24, the air flowing through the several outlets or nozzles directly into the flues or throats 17. The air from the bottom and top pipes is blown across the flues or throats, whereas the air from the vertical pipes is 100 blown across the flues and in the case of the nozzles 28, 29 the air flows in inclined paths converging rearwardly of the piers. By blowing the air into the flues from the several directions it is clear that the air 105 currents cross and intersect within the flues, and thus the inflowing air breaks up the currents of the gaseous products and is intermingled thoroughly therewith, the additional oxygen thus supplied burning the 110 carbon in the smoke.

As shown in Fig. 3, the blast nozzles in two adjacent piers are horizontally arranged so as to partake of an inclined relation to the line of flow of the gases into and through the chamber or space intervening said piers; in other words, the blast nozzles on one side of the chamber or space are inclined in one direction, whereas the blast nozzles on the opposite side of the space or chamber are 120 inclined oppositely to the first named nozzles, said oppositely positioned nozzles occupying a converging relation rearwardly of the space or chamber, whereby the blasts projected through said nozzles converge 125 rearwardly of the chamber as graphically depicted by the dotted lines in Fig. 3. In a similar manner, the nozzles at the bottom of the chamber and the nozzles at the arch or top of the chamber are inclined toward 130

each other and toward the line of flow of the gases through the space or chamber. As a result of the inclination of the nozzles, the blasts of steam and air are projected into the chambers or spaces between the piers so that the blasts impinge the outflowing furnace gases in a manner not only to intensify the heat but to break up the currents of gases. In my invention the nozzles are provided with elongated blast outlets in the form of slots so as to obtain a sheet of steam and air as distinguished from a mere jet, and as the sheets of steam and air spread out and are projected at high speed and in inclined paths across the outflowing furnace gases, the sheets from the nozzles thus intersect across the line of flow of the gases, with the result that the steam and air cover the cross sectional area of the space or chamber, thus increasing the efficiency of operation of the apparatus.

Furthermore, the arched roofs to the spaces or chambers between the piers act to reflect the heat upon the converging sheets of steam and air, and, further, the spaces or chambers between the piers extend for appreciable or substantial distances rearwardly from the front face of the bridgewall, the effect of which is to thoroughly commingle the inflowing steam and air with the furnace gases and to secure combustion of the gases to such a marked degree as to obtain great economy in the consumption of fuel and increased steaming capacity in the boiler.

Having thus fully described the invention, what I claim as new and desire to secure by Letters Patent is:

1. In a furnace, the combination with a bridgewall, of a plurality of piers erected upon said bridgewall and extending rearwardly from the front thereof so as to produce intervening combustion chambers of appreciable width and depth over said bridgewall, nozzles positioned in the sides of the combustion chambers and in inclined relation to the line of flow of the furnace gases through said combustion chambers, the nozzles at the respective sides of each chamber being inclined oppositely to each other and operating to direct sheets of steam and air in converging paths within the respective chambers and rearwardly of the front portion of the bridgewall, and a supply conduit communicating with said nozzles.

2. In a furnace, the combination with a bridgewall, of a plurality of piers and arches erected upon said bridgewall and extending rearwardly from the front thereof so as to produce combustion chambers of appreciable width and depth extending rearwardly from the front part of the bridgewall, nozzles positioned in the sides of the combustion chamber and in inclined relation

to the line of flow of the furnace gases through said combustion chambers the arched roofs of which reflect the heat downwardly, the nozzles at the respective sides of each combustion chamber being inclined in opposite directions to each other and operating to direct sheets of steam and air on lines converging within the respective combustion chambers and rearwardly of the front portion of the bridgewall, and a supply conduit communicating with said nozzles.

3. In a furnace, the combination with a bridgewall, of a plurality of piers erected upon the bridgewall and extending rearwardly from the front portion thereof and spaced to produce combustion chambers of appreciable width and depth extending rearwardly from said front portion of the bridgewall, blast nozzles positioned in the sides of the combustion chambers and in inclined relation to the line of flow of the furnace gases through said combustion chambers, said nozzles on one side of each combustion chamber being inclined in an opposite direction to the inclination of the nozzles on the opposite side of the chamber and each nozzle having a blast outlet in the form of a slot so that the nozzles direct sheets of steam and air on converging lines within the respective combustion chambers and rearwardly of the front portion of the bridgewall, and a supply conduit communicating with said nozzles.

4. In a furnace, the combination with a bridgewall, of a plurality of piers erected thereon and spaced to produce combustion chambers the roofs of which are arched and which chambers are of such dimensions as to extend for appreciable distances rearwardly from the front portion of the bridgewall, nozzles positioned in the sides of the combustion chambers and incased in the piers, arched roofs and bottoms of the combustion chambers, said nozzles on one side of the chamber being inclined oppositely to the nozzles on the opposite side of the chamber and all the nozzles being inclined to the line of flow of the furnace gases passing through said chambers so that sheets of steam and air are directed to flow on converging lines within the respective combustion chambers, and a supply conduit communicating with said nozzles.

5. In a furnace, the combination with a bridgewall, of a pier and arches erected upon the bridgewall and spaced to form a plurality of combustion chambers the dimensions of which are such as to extend for appreciable distances rearwardly from the front portion of the bridgewall, blast pipes incased in the walls of said combustion chambers, and nozzles communicating with said pipes and each inclined to the line of flow of furnace gases through said com-

burntion chambers, the nozzles on one side of each chamber being inclined in an opposite direction to the inclination of the nozzles on the opposite side of the chamber and said oppositely positioned nozzles being located in the sides of the combustion chambers and operating to direct sheets of steam and air on converging lines within the respective combustion chambers and rearwardly of the front portion of the bridgewall.

6. In a furnace, the combination with a bridgewall, of piers and arches positioned over the same and spaced relatively to each other so as to form intervening combustion chambers the width and depth of which are such as to extend for appreciable distances rearwardly from the front portion of said bridgewall, blast pipes embedded in the piers and arches and extending around each combustion chamber, and blast nozzles communicating with said pipes and positioned at an angle to the line of flow of furnace gases through said chambers, the nozzles on one side of the chamber being inclined in an opposite direction to the nozzles on the opposite side of the chamber and said oppositely inclined nozzles being located in the sides of the combustion chambers and

operating to direct sheets of steam and air 30 in converging paths within the respective combustion chambers.

7. In a furnace, the combination with a bridgewall, of piers and arches positioned thereon and spaced relatively to each other 35 to produce combustion chambers extending for appreciable distances rearwardly from the front portion of the bridgewall, blast nozzles positioned in inclined relation to the line of flow of furnace gases through said 40 combustion chamber, the nozzles on one side of each chamber being inclined in an opposite direction to the inclination of other nozzles in the opposite side of the same chamber and each nozzle being provided 45 with an elongated blast outlet, said nozzles being located in the sides of the combustion chambers and operating to direct sheets of steam and air on converging lines within the respective combustion chambers and the 50 sheet of steam and air from each nozzle being free to spread so as to intersect with the sheet of steam and air from an adjacent nozzle or nozzles, and a supply conduit communicating with said nozzles. 55

In testimony whereof I have hereunto signed my name.

ORLAND D. ORVIS.
